UNITED STATES PATENT OFFICE

153,250

DESIGN FOR A FISH LURE

William C. Badge, Detroit, Mich.

Application January 2, 1947, Serial No. 135,886

Term of patent 7 years

(Cl. D31—4)

To all whom it may concern:

Be it known that I, William C. Badge, a citizen of the United States, residing at Detroit, Wayne County, Michigan, have invented a new, original, and ornamental Design for a Fish Lure, of which the following is a specification, reference being had to the accompanying drawings, forming a part thereof, wherein:

Fig. 1 is a side elevation,
Fig. 2 is a top plan view,
Fig. 3 is a bottom plan view,
Fig. 4 is a rear end elevation, and
Fig. 5 is a front end elevation of a fish lure
embodiment my new design.

I claim:

The ornamental design for a fish lure, as shown.
WILLIAM C. BADGE.
